UNITED STATES PATENT OFFICE.

GEORGE E. LEE, OF CLEVELAND, OHIO, ASSIGNOR TO THE GEORGE E. LEE COMPANY, OF CLEVELAND, OHIO, A CORPORATION OF OHIO.

HEAT CONTROL FOR LINOTYPE MELTING-POTS.

1,208,587.

Specification of Letters Patent. Patented Dec. 12, 1916.

Application filed June 1, 1915. Serial No. 31,343.

To all whom it may concern:

Be it known that I, GEORGE E. LEE, a citizen of the United States, residing at Cleveland, in the county of Cuyahoga and State of Ohio, have invented a certain new and useful Improvement in Heat Control for Linotype Melting-Pots, of which the following is a full, clear, and exact description.

This invention relates to linotype machines, the object of the invention being to provide mechanism for controlling the heating of the various portions of the melting pot of a linotype machine.

Generally speaking, the invention comprises the elements and combinations thereof set forth in the accompanying claims.

Reference should be had to the accompanying drawings forming a part of this specification, in which—

20 Figure 1 is an elevation with the parts in section of a melting pot embodying my invention; and Fig. 2 is a top plan view of the showing in Fig. 1. Fig. 3 is an elevation with portions in section showing a part of 25 the thermostat control.

In the casting of lines or slugs in a linotype machine it is, practically speaking, necessary that the temperature of the metal which is injected into the mold be controlled 30 so as not to be too hot or too cold, and this condition must be regularly maintained under varying conditions of operation of the melting pot if uniform success in casting is to be obtained.

35 When the metal supplied to the mold is too hot, there are a number of troubles which develop either singly or together. Overheated metal may produce back-squirting at the time the metal is forced into the mold.

40 Furthermore, metal too hot produces imperfect slugs,—sometimes the slugs are hollow, not containing sufficient metal to permit them to be used in printing. Or, again, the slugs may be soft, so that the ejector blade 45 will sink into the slug at the time the slug is being pushed from the mold, this being brought about by the fact that the metal is so hot that it does not have sufficient time to cool during the casting operation to be 50 in condition solid enough to prevent the ejector blade sinking into them. Hot metal frequently produces sunken letters or air cells underneath the surface of the letters, in which condition the slugs can not resist 55 pressure exerted upon them in the process

of printing or the pounding in of the matrices in the process of making stereotype plates. Furthermore, hot metal causes a warping of the mold and also has a very deteriorating action upon the metal (brass) of which the matrices are made. When the metal injected into the mold is too cold, it is apt to produce a freezing of the metal in the mouthpiece, frequently preventing continuous casting of slugs, or to result in an imperfect slug, due to the fact that the metal not being hot enough does not perfectly fill the mold. In either event an unsatisfactory and unusable slug is made, and, accordingly, metal too hot or too cold must be avoided. 60 However, the regulation of the temperature of the metal supplied to the mold becomes a matter requiring some skill and attention in controlling, especially under the varying conditions under which a linotype machine 65 may operate.

There are times when the linotype machine is wholly or fairly inactive, at which time the temperature of the mouthpiece must be maintained at such a temperature that the 70 metal will not chill when subsequently as the machine is used it passes through the mouthpiece. At other times the machine is working actively and with great rapidity, so that fresh supplies of metal are continually 75 coming in contact with the mouth portion of the melting pot, and the walls of the mouth portion absorb large amounts of heat from the metal. Obviously, the amount of 80 heat supplied externally to the mouthpiece 85 must be shut off, or at least greatly reduced. And the heat supplied by the heating burner for the mouthpiece must be decreased in the same proportion as heat is supplied to the mouthpiece by the hot metal passing through 90 it. Furthermore, when lines or slugs of different length or thickness are cast, the quantity of metal passing through the mouthpiece varies and under such conditions, the 95 temperature of the mouthpiece and the metal must be kept just right, so that all in all there is quite a variety of regulation of the 100 heating of the mouthpiece of a linotype machine necessary to take care of all its various 105 phases of operation.

The usual melting pot of a linotype machine contains a portion wherein is contained the bulk of the melted metal, a throat portion and a mouth portion. As is well known, the metal is forced through the throat and 110

the mouth portion by means of a pump. As the metal is used from the pot additional metal is added in the form of slugs, which are merely dumped into the pot and are 5 melted by the heat which is applied to the pot. Naturally at such times as metal slugs are dumped into the pot the temperature of the metal is lowered. Consequently it is necessary at such times to supply an increased amount of heat to the pot in order 10 to quickly melt and raise the melted metal to the proper temperature. Naturally, the heating of this metal must be in as quick a manner as possible in order that metal of 15 the proper temperature for casting may be supplied through the mouthpiece, and not require that the machine be slowed down in its operation in order to wait for the raising of the temperature of the melted metal. On 20 the other hand when the machine is in operation the heat supplied to the pot should be a minimum, that is, just enough to maintain the metal at proper temperature.

While the mouth is a portion of the metal 25 pot, the considerations governing the temperature of the mouthpiece are quite different from the considerations governing the heat supplied to the melting pot. When the linotype machine is not in use, the amount 30 of heat supplied to the melting pot properly should be at a minimum, being just sufficient to maintain the metal at a proper temperature. On the other hand at this time the temperature of the mouth of the melting pot 35 should be at its maximum, because it is at that time receiving no heat which would naturally be transmitted to the walls of the mouth when conditions are such that metal passes through the mouth at frequent inter- 40 vals. On the other hand, when the linotype machine is being used, and slugs are rapidly being made, the addition of fresh metal to the melting pot requires that a large quantity of heat be supplied to the melting pot 45 and a minimum amount of heat be supplied to the mouth, for at this time the walls of the mouth will receive a great amount of heat due to the contact of the hot metal with the walls of the mouthpiece.

50 The temperature of the mouthpiece should always be maintained as nearly constant as is practical, so that at all times the mouthpiece will be in condition to receive the metal which is pumped from the melting pot.

55 The object of this invention is to provide automatic means which will regulate the heat supplied to the melting pot, and other automatic means which will regulate the heat supplied to the mouthpiece, the ar- 60 rangement being such that the heat supplied to each of these sources is independently controlled.

In the present disclosure of my invention I have illustrated the melting pot with its 65 throat and mouth heated by the use of gas.

It will, however, be apparent that any other method of heating may be employed and I do not limit myself to the precise manner of heating herein shown.

Referring to the drawings, the melting 70 pot is generally represented at 1; the throat of the melting pot at 2; and the mouth of the melting pot at 3. The melting pot herein shown is of the usual shape and construction, and no extended description need 75 be given. The pot is provided with a central well 4, which is adapted to receive the plunger that forces the metal through the throat and mouth of the pot. Beneath the pot I have shown a burner 5. This burner so 80 has an auxiliary burner 6, the flame of which auxiliary burner is directed against the under side of the throat of the melting pot. The burners 5 and 6 are supplied through a mixer 7 by a valved pipe 8. This pipe connects with the outlet portion of a thermostat 9. The inlet pipe of the thermostat is represented at 10, and this pipe 10 is fed from a supply pipe 11. A heat-receiving 85 element 12 of a thermostatic couple is operatively connected with a lever 13 which is pivoted within the casing 14 at 15. This lever mechanism is secured to a valve 16 which co-operates with a sleeve 17 to regulate the flow of gas through the casing 14. Ex- 90 tending beneath the mouthpiece 3 is a casing 18 which is formed integral with the mouthpiece, so that heat applied to the casing 18 will be distributed to the mouthpiece by the conduction of the heat through the metal. The casing 18 is adapted to receive a heat- 95 receiving element 19 of a thermostatic couple. This heat-receiving element is connected with a lever mechanism within the casing 20, operating a valve, etc., in the same manner as previously described. The gas is 100 supplied through the pipe 11 to the pipe 21 passing through the casing 20 and from the casing to the pipe 22. This pipe supplies 105 gas to the mixer 23 and the mixer to the burner 24. This burner is placed beneath the mouthpiece and beneath the casing which contains the thermostat element 19.

It will be seen from the construction de- 110 scribed that the heat supplied to the melting pot proper is entirely governed by the thermostat generally represented at 13, while the heat which is supplied at the mouthpiece 3 is entirely governed by the thermostat generally represented at 20.

The thermostat which controls the heating of the mouthpiece is a very sensitive instrument, that is to say, it must respond very quickly to temperatral changes, inasmuch as the control of the heating of the mouthpiece must be quickly accomplished under the changing conditions under which the machine is operated.

By using the two thermostats in their re- 120 spective connections, I am enabled to con-

trol the supply to the mouthpiece in a manner which is absolutely independent of the control of the heat to the melting pot proper, so that each portion of the melting 5 pot functions in the manner in which it should with respect to the proper casting of metal slugs. And I have found in practice that by this method of controlling the heating of the various portions of the metal 10 pot I am enabled to produce a much higher percentage of perfect slugs than can be done without the method of controlling the heating herein described.

Having thus described my invention, what 15 I claim is:—

1. The combination with a melting pot for a type line casting machine comprising a reservoir portion, a throat portion, and a mouth portion, means for heating the reservoir portion and the mouth portion, and separate means for automatically and independently controlling the amount of heat supplied to the reservoir portion and mouth portion, in accordance with the heat condition 20 of the said portions.

2. The combination with a melting pot for linotype machines, said melting pot comprising a reservoir portion, a throat and mouthpiece, means for heating the reservoir 25

portion, independent means for heating the mouth portion, a thermostat associated with the reservoir portion for controlling the means which supplies heat to the reservoir portion, a thermostat associated with the mouth portion and adapted to control the means which supplies heat to the mouth portion.

3. The combination with a melting pot for a linotype machine, said melting pot comprising a reservoir portion, a throat portion and a mouth portion, means for heating the reservoir portion, and independent means for heating the mouth portion, a thermostat having a thermostatic couple which extends into the reservoir portion, 40 said thermostat controlling the heat supplied to the reservoir portion, a thermostat having a thermostatic couple which extends longitudinally of the mouth portion, said thermostat controlling the heat supplied to 45 the mouthpiece by its heating means.

In testimony whereof, I hereunto affix my signature in the presence of two witnesses.

GEORGE E. LEE.
